UNITED STATES PATENT OFFICE.

ANDREW E. MILLER, OF LOUISVILLE, MISSISSIPPI.

MECHANICAL MOVEMENT.

1,131,851.

Specification of Letters Patent.

Patented Mar. 16, 1915.

Application filed January 20, 1913. Serial No. 743,176.

To all whom it may concern:

Be it known that I, ANDREW E. MILLER, a citizen of the United States, residing at Louisville, in the county of Winston and State of Mississippi, have invented a new and useful Mechanical Movement, of which the following is a specification.

One object of the present invention is to provide a spring motor of novel and improved form adapted to be employed for actuating the movable element of a churn.

With the foregoing and other objects in view which will appear as the description proceeds, the invention resides in the combination and arrangement of parts and in the details of construction hereinafter described and claimed, it being understood that changes in the precise embodiment of invention can be made within the scope of what is claimed without departing from the spirit of the invention.

In the drawing:—Figure 1 shows the invention in side elevation; Fig. 2 is an end elevation; Fig. 3 is a vertical longitudinal section; Fig. 4 is an elevation of the cam wheel; and Fig. 5 is a transverse section on the line 5—5 of Fig. 1.

In carrying out the invention there is provided a supporting structure comprising a base 1. Fixed to and upstanding from the base 1 is a U-shaped frame 2, sustained by means of a brace 3. For the sake of compactness, the frame 2 may be contracted intermediate its upper and lower ends as indicated at 4.

Journalized for rotation in the frame 2 is a winding shaft 5 to which is secured one end of a coil spring 6, the other end of which is secured to a drum 7, provided with outstanding handles 8, the drum 7 being secured to a ratchet wheel 9 having a collar 10 which is journalized on the winding shaft 5 to one side of the frame 2. A pawl 11 is pivoted to the frame 2 and is sustained by a spring 12 to engage the ratchet wheel 9.

Secured to the winding shaft 5 and located between the side portions of the frame 2 is a pinion 14 which meshes into a pinion 15 secured to a shaft 16 journalized in the frame 2. The shaft 16 carries a pinion 17 meshing into a pinion 18 secured to a shaft 19 journaled in the frame 1 above the shaft 16.

Secured to one end of the shaft 19 and located to one side of the frame 2 is a wheel

20 provided in its inner face with a cam groove 21, contracted in its intermediate portion and adjacent the shaft 19, as indicated at 22 to form oppositely extended loops 23. A lever 24 is fulcrumed as indicated at 25 upon an arm 26 which outstands from the frame 2. At one end, the lever 24 is equipped with a roller 27 adapted to traverse the groove 21 in the cam wheel 20. A weight 28 is slidable upon the lever 24 between the fulcrum 25 and the cam wheel 20, the weight 28 being held in adjusted positions along the lever by means of a set screw 29. The outer end of the lever 24 is loosely connected as indicated at 30 with a dasher rod 31 mounted to reciprocate in a receptacle 32 which is supported by the base 1. The dasher rod 31 reciprocates in a lid 33 which rests upon the top of the receptacle 32. Located above the lid 33 and surrounding the dasher rod 31 is a ring 34, and a frusto-conical cover 35 which may be fashioned from netting, contacts the ring 34 with the periphery of the lid 33. Located between the depending flange of the lid 33 and the body portion of the receptacle 32 is a coiled spring 36, one end of which is secured as indicated at 37 to the lid 33. The spring 36 surrounds and embraces closely, the neck of the receptacle 32.

Projecting from the frame 2 is an arm 38 to which is secured an overhanging support 39. Secured to the lower edge of the arm 38 and alined vertically with the end of the support 39 is a bracket 40. Screws 41 are threaded into the support 39 and into the bracket 40, the screws receiving for rotation a worm 42 which meshes into a wheel 43 secured to a shaft 44 journalized in the arms 38. Secured to the worm 42 to rotate therewith is a yoke 45 upon which is pivoted a pair of counter-weighted arms 46 having approaching angularly protruding extensions 47 adapted to bear upon the upper end of a spool 48 which is journalized upon the worm 42 above the threaded portion thereof. The spool 48 rests upon one end of a lever 49 which is fulcrumed as indicated at 50 upon one of the arms 38, and is adjusted by means of a screw 49^b threaded into a cleat 49^a on the arm 38.

All of the shafts and pinions hereinbefore described may be retained in proper relation with respect to the frame 2 by means of collars 51 held in place by set

screws 52, the construction being such that any part may be removed readily for renewal or for repair.

The moving parts of the structure may be housed within a casing 53 of any sort, supported by the frame 2.

The actuating spring 6 may be put under tension by rotating the drum 7 and the ratchet wheel 9 through the medium of the handles 8, the back stop pawl 11 exercising its obvious function. The spring 6, when under tension, will drive the shaft 5, the pinion 14 meshing into the pinion 15 and actuating the shaft 16. The pinion 17 on 15 the shaft 16 will drive the pinion 18, the pinion 18 rotating the shaft 19 and the shaft 19 rotating the cam wheel 20. When the cam wheel 20 is rotated, one end of the lever 24 will ride in the cam groove 21, and 20 owing to the peculiar construction of the cam groove, as clearly outlined in Fig. 4, two strokes will be imparted to the lever 24 at each rotation of the cam wheel 20. When the lever 24 is reciprocated, vertical reciprocatory motion will be imparted to the dasher 31 which is mounted to operate within the churn receptacle 32. At this point it 25 may be noted that since the lid 33 of the receptacle is provided with the contractile coil, spring 36, the lid may be assembled readily with receptacles of different diameters. When the shaft 16 and the pinion 17 are rotated, the pinion 17, meshing into the pinion 14, will actuate the worm 42. When 30 the worm 42 is rotated, the counter-weighted arms 46 will fly outwardly, the extensions 47 bearing upon the upper end of the rotatably mounted spool 48 and thrusting the spool 48 downwardly upon the upper 35 end of the lever 49. Since the lever 49 is mounted to swing, as indicated at 50, a brake pressure will be applied to the spool 48 and to the worm 42, the speed being thereby held back. Owing to the fact that 40

the lever 49 is adjustably supported at 49^b, 45 the brake pressure may be regulated readily. The speed with which the worm 42 rotates may be limited further by adjusting the pressure with which the screws 41 bear against the ends of the worm. 50

As will be understood readily, the set screw 29 may be loosened, permitting the weight 28 to be shifted along the lever 24. Owing to the provision of the weight 28, the lever 24 may be counter-balanced, to off-set 55 the weight of the dasher rod 31.

Having thus described the invention, what is claimed is:—

In a device of the class described, a frame; a wheel journaled on the frame and 60 provided with a cam groove in its side face; means for driving the wheel; a lever disposed substantially at right angles to the groove-carrying side face of the wheel, one end of the lever being received in the 65 groove; a pivot element connecting the lever intermediate its ends with the frame; a driven element carried by the outer end of the lever and supported solely by the lever; a weight mounted for sliding adjustment on 70 the lever between the pivot element and the wheel; and means for securing the weight in adjusted positions on the lever; the weight being adjustable to counteract the weight of the driven element and to hold the lever 75 in equilibrium, thereby to lessen the friction between the groove-received end of the lever and the wheel, the disposition of the lever at right angles to the wheel permitting the weight to be held close to the wheel, thereby 80 giving the weight a maximum moment.

In testimony that I claim the foregoing as my own, I have hereto affixed my signature in the presence of two witnesses.

ANDREW E. MILLER.
